COMBINED TRANSPARENCY PROJECTOR AND VIEWER

Richard P. Fuller, 11758 Collins St.,
North Hollywood, Calif.

Filed May 28, 1962, Ser. No. 70,322

Term of patent 7 years

(Cl. D61—1)

FIG. 1.

FIG. 3.

FIG. 2.

FIG. 5.

FIG. 4.

FIG. 6.

FIG. 8.

FIG. 7.

FIG. 9.

FIG. 10.

FIG. 1 is a top plan view of a combined transparency projector and viewer showing my new design as it would appear when subject to use as a projector;
 FIG. 2 is a side elevation thereof;

FIG. 3 is an end elevation thereof;

FIG. 4 is a side elevation of the side opposite that shown in FIG. 2;

FIG. 5 is an end elevation of the end opposite that shown in FIG. 3;

FIG. 6 is a top plan view of the combined transparency projector and viewer shown in FIG. 1 as it would appear when in use as a viewer;

FIG. 7 is a side elevation thereof;

FIG. 8 is an end elevation thereof;

FIG. 9 is a side elevation of the side opposite that shown in FIG. 7; and

FIG. 10 is an end elevation of the end opposite the end shown in FIG. 8.

I claim:

The ornamental design for a combined transparency projector and viewer, as shown.
